Specification for Design.

Patented Dec. 9, 1919.

Application filed September 26, 1918. Serial No. 255,867. Term of patent 14 years.

To all whom it may concern:

Be it known that I, ADAM SOLLEN, a citizen of Russia, residing in the city of New York, county of New York, and State of New York, have invented a new and original Design for Trousers, of which the following is a specification, reference being had to the accompanying drawing, forming a part thereof, wherein—

Fig. 2 is a view in rear elevation thereof.

What I claim is—

The ornamental design for trousers as shown.

ADAM SOLLEN.
